UNITED STATES PATENT OFFICE

163,372

SUPPORTING STAND FOR POCKET WATCH

Charles A. Cone, Troy, Mont.

Application February 2, 1951, Serial No. 14,079

Term of patent 14 years

(Cl. D42—1)

To all whom it may concern:

Be it known that I, Charles A. Cone, a citizen of the United States and resident of Troy, in the county of Lincoln and State of Montana, have invented a new, original, and ornamental Design for a Supporting Stand for Pocket Watch, of which the following is a specification, reference being had to the accompanying drawing, forming a part hereof.

The figure is a perspective view showing the front and one side of a supporting stand for pocket watch, illustrating my new design, the side and back not shown are substantially the same as the side shown.

I claim:

The ornamental design for a supporting stand for pocket watch as shown and described.

CHARLES A. CONE.
